HEEL-SEAT FITTING MACHINE

Charles G. Brostrom, Peabody, Mass., assignor to
 United Shoe Machinery Corporation, Paterson,
 N. J., a corporation of New Jersey

Application July 5, 1934, Serial No. 733,714

25 Claims. (Cl. 12—31.5)

This invention relates to the manufacture of shoes and is illustrated as embodied in a heel-seat fitting machine.

In order to prepare a shoe to which a sole has been attached for the reception of a wood heel it is customary to trim material from the margin of the heel-seat portion of the sole, thereby reducing the heel seat portion of the sole to the form of a tongue which is sufficiently large to serve as a base to which the heel may be effectively secured and which is of suitable size to permit the rim of the attaching face of the heel snugly to engage the overlasted portion of the shoe upper. During the heel-seat fitting operation a pair of shoulders extending transversely of the sole are formed at the forward lateral portions of the reduced heel seat, which shoulders are shaped and arranged to engage the breast of the heel positioned upon the shoe.

It is an object of this invention to provide an inexpensive machine operable to fit the heel seats of shoes for the reception of heels. With the above object in view and in accordance with a feature of this invention the illustrated machine comprises a support for a shoe, a flexible cutter, mechanism for operating the cutter, guides constructed and arranged to constrain an operating portion of the cutter for movement in a path of predetermined curvature, and means for guiding the support past the operating portion of the cutter to reduce the heel-seat portion of the sole of a shoe mounted upon the support. In the illustrated machine a portion of the cutter which has the form of a strip knife, is flexed by the guides to form the curved trimming or operating portion of the knife to which the shoe is presented. In order to present the shoe to the trimming portion of the knife, the support is guided in a U-shaped path past the trimming portion.

The support is also mounted for rectilinear movement toward and away from the trimming portion of the knife. The trimming portion of the knife is tilted transversely so as to cause its cutting edge to face the support as the shoe upon the support is raised thereby to cut a heel-breast receiving shoulder at one end of the heel-breast line of the sole. Upward movement of the support toward the knife is stopped by engagement of one of the knife guiding members with the overlasted counter portion of the shoe. During the removal of the margin of the heel-seat portion of the sole the overlasted counter portion of the shoe upper is in engagement with the bottom face of the guide member as the shoe upon the support is moved in the U-shaped path, the

leading end of the guide member serving as a plow which engages within the rand crease of the shoe. After the heel-seat reducing cut has progressed around the heel end of the shoe to a point adjacent to the opposite end of the heel-breast line the operator tilts the knife so that its cutting edge faces away from the support which is then lowered, thereby causing the knife to cut a heel-breast receiving shoulder at the opposite end of the heel-breast line. When the support has been lowered the shoe is removed therefrom and is replaced by another shoe.

With the above and other objects and features in view, the invention will now be described in connection with the accompanying drawings and pointed out in the claims.

In the drawings,

Fig. 1 is a side elevational view of the illustrated heel-seat fitting machine;

Fig. 2 is an enlarged side elevational view of the head of the illustrated heel-seat fitting machine, portions of which have been broken away;

Fig. 3 is a perspective view of the head of the machine;

Fig. 4 is an enlarged view illustrating the above machine in the process of forming a heel-breast receiving shoulder;

Fig. 5 is an illustrative view showing the machine in the process of reducing the heel-seat portion of the sole of a shoe;

Fig. 6 is a view similar to Fig. 5 but showing the machine adjusted so that the cutting edge of the knife is straight;

Fig. 7 shows a clamp by means of which the shoe is secured to a support during the heel-seat fitting operation;

Fig. 8 is a perspective view of the rear end of an inverted shoe the heel-seat portion of the sole of which has been reduced by the illustrated machine; and

Fig. 9 is an illustrative sectional view showing the angular relation of the sole and the knife during the shoulder forming operation.

In order to prepare a shoe 20 having an attached sole 22 for the reception of a wood heel 24 (Fig. 8) it is customary to trim the heel-seat portion of the sole by a beveling cut 26 thereby reducing the heel seat to the form of a tongue as shown at 28 and to form a pair of heel-breast receiving shoulders 30, 31 which extend transversely of the sole from the forward lateral portions of the reduced heel seat 28.

The illustrated machine comprises a flexible cutting blade or strip knife 32, spaced guide members 34, 36 for flexing the cutting blade 32 to 55

curve the trimming portion 38 thereof, and a support 40 upon which the shoe is secured by a clamp 42 and which may be guided in a U-shaped path past the trimming portion of the knife.

5 The operating parts of the machine are supported by a standard 44 (Fig. 1) upon which a table 46 is adjustably secured. Bolted to the forward end of the table 46 is a bifurcated bracket 48 which, through the provision of a bolt and nut 10 connection 49, is secured to a depending flange 50 of a housing 52 within which a cutter-operating slide 54 is reciprocated. The end of the slide 54 is pivotally connected to an eccentric strap 56 driven by an eccentric 58. The eccentric 58 is keyed to a shaft 66 upon which is mounted a pulley 62 (Fig. 2) driven by a belt 64 from, for example, an electric motor 66 (Fig. 1).

In order to support the knife 32 which is thin and narrow and to tilt the same relatively to the support in order to form the heel-breast receiving shoulders 30, 31 the illustrated machine is provided with a rocking beam 68 (Fig. 3) mounted upon a bored bearing sleeve 70 (Fig. 2) which is secured to the housing 52 by a screw 72. Secured 25 to and extending forwardly of the beam 68 is a bracket 74 which serves as a support for the guide members 34, 36. Slots 76 (Fig. 5) and 78 of the guide members 34, 36, respectively, are of suitable size to receive the strip knife 32 and to flex the same to curve its cutting portion 38. To insure that the cutting portion 38 shall not be deformed substantially by the work during the sole-trimming operation a brace 80 which is secured to the bracket 74 engages the convex side of the knife.

35 The curvature of the trimming portion 38 of the knife 32 may be changed after releasing the brace 80 from its clamped position with relation to the bracket 74, by pivotally adjusting the guide member 36 about a pin 82 (Figs. 3 and 5) carried by a slide 83 which may be adjustably secured in different positions along a guideway 84 of the bracket 74. Such pivotal adjustment is maintained through the provision of a set screw 85 which is in threaded relation with the slide 83 and passes 40 through an arcuate slot 88 in the guide 36. After the adjustment has been made the brace 80 is again moved into engagement with the convex side of the knife 32 and is clamped to the bracket 74. The slide 83 may be adjusted heightwise relatively to the guideway 84 through the provision 45 of a screw and slot connection 85 (Fig. 2).

The lower end of the knife 32 is secured to the operating slide 54 by a clamp plate 90 which is secured to the arm by a screw 92, the knife extending through the bore of the bearing sleeve 70 and engaging within the slots 76, 78 of the guide members 34 and 36, respectively. In order readily to replace a dull cutting section 38 of the knife by a sharp cutting section the knife has the form 55 of a coil which is wound around a drum 94 (Fig. 2) supported by an arm 96 of the bracket 74. A sharpened length of the strip knife 32 may be readily unrolled by releasing a clamp screw 98 carried by an angle arm 100 secured to the bracket 60 74 and pulling the knife lengthwise against the pressure of a friction spring (not shown) through the slots 76 and 78 and through the bore of the bearing sleeve 70. The blunt portion of the lower end of the knife is then easily broken off preparatory to clamping the knife to the operating arm 54.

70 The shoe 20, the attached sole 22 of which is to have its heel-seat fitted for the reception of a heel 24, is mounted bottom side up upon the support 40, the heel portion of which has a shape simi-

lar to that of the heel portion of the inside of the shoe. The sole is clamped securely to the support 40 just forwardly of the heel-breast line 106 of the sole by a pair of opposed arms 102 (Fig. 7) of the clamp 40 which is carried by a bracket 104.

5 The shoe supporting and guiding mechanism is mounted upon an upright rod or post 108 (Fig. 1) which is slidably mounted in a forward extension 110 of the standard 44 and is normally urged upwardly by a spring 112, the lower end of the 10 spring being connected to a treadle 114 which may be depressed for the removal of a shoe from the machine. In order to limit the upward movement of the rod 108 under tension of the spring 110 the rod is provided with a collar 116 constructed and 15 arranged to engage the forward extension 110 of the frame of the machine.

An angular member 118 (Figs. 1 and 3) is secured by bolts to a plate 120 which is formed integral with or is rigidly secured to the upper end of the rod 108, a pair of guide rollers 122 (Fig. 3) being mounted upon the upper surface of the angular member 118 through the provision of screws 124. One of the rollers 122 is of suitable width to fit within a U-shaped slot 126 formed 25 in a slide plate 128, the rollers 122 being suitably spaced to include between them a U-shaped rib 130 of the slide plate 128. A cover piece 132 bridges the space between the rollers 122 and retains the plate 128 which is movable in a U-shaped 30 path, upon the angular member 118.

Lateral adjustment of the support 40 relatively to the sliding plate 128 may be readily effected by moving the pedestal along a dovetail guideway 142 (Fig. 3) of the support bar 104 after releasing a clamp screw 144 (Fig. 2). In order that the support 40 may be angularly adjusted relatively to the plate 128 in directions indicated by arrows 134 (Figs. 2 and 3) thereby to vary the angle of the beveling cut 26 by which the heel-seat portion 28 of the sole is reduced, the support 40 is provided with an arcuate depending portion 136 constructed for sliding engagement along an arcuate guideway 137 (Fig. 3) of a pedestal 138. A screw 140 which passes through split upper 45 portions of the pedestal 138 clamps the support 40 rigidly to the pedestal and may be released to permit angular adjustment of the support relatively to the pedestal. By providing the above 50 adjustments the shoe may be accurately positioned upon the support 40 relatively to the trimming portion 38 of the knife. The plate 128 may be replaced by another plate having a rib 138 of a different shape in accordance with the shape to which the heel seat is to be trimmed.

55 During substantially the entire heel-seat reducing operation the overlasted counter portion 145 (Fig. 8) of the upper of the shoe 20 is held by the spring 112 against the bottom face 146 (Fig. 3) of the guide member 34 which therefore 60 also serves as a guard. The top face 148 (Figs. 4 and 5), as well as the bottom face 146, of the guide member 34 substantially merges with the sides of the strip knife 32 which projects from the forward portion of the guide member. The 65 lower portion 150 (Figs. 4 and 5) of the guide member 34 extends beyond the cutting edge of the knife 32. The bottom and the top faces 146 and 148 of the guide member 34 thus operate as a plow, progressively raising the margin of the 70 heel-seat portion of the sole from the overlasted counter portion 152 of the shoe as the shoe mounted upon the support 40 is moved in a U-shaped path to form the beveling cut 26.

75 Before the guide member 34 operates as above

described the heel-breast receiving shoulder 30 is formed to permit the guide to be inserted between the overlasted counter portion 145 (Fig. 8) of the upper of the shoe and the marginal portion which 5 is to be removed from the sole. The position of the heel-breast receiving shoulders 30, 31 is determined by a mark which has been previously drawn across the sole along the heel-breast line 106. The heel-breast receiving shoulder 30 is 10 formed by causing the narrow strip knife 32 to face downwardly toward the sole as illustrated in Fig. 4 as the shoe is raised with the support 40. The trimming section 38 of the knife is tilted to cause its cutting edge to face downwardly by 15 rocking the beam 68 in a counterclockwise direction (as shown in Fig. 4) about the bearing sleeve 70. Such rocking movement is effected by actuating a two-way treadle 154 (Fig. 1) pivotally connected to a rod 156 which is universally connected to a lug 158 secured to the beam 68. As 20 the trimming section 38 of the knife finishes the shoulder-forming cut the operator moves the treadle 154 to a neutral or horizontal position such as is illustrated in Fig. 1. The portion 150 (Fig. 5) of the bottom face of the guide which projects forwardly of the cutting edge of the knife engages the overlasted counter portion 145 of the shoe upper at the end of the shoulder-forming operation and prevents the knife from 25 injuring the shoe upper. After the heel-breast receiving shoulder 30 has been formed the heel-seat portion of the sole is reduced as above described, the shoe being moved in a U-shaped path past the trimming portion 38 of the knife, the 30 forward or plow portion of the guide 34 progressively engaging within the rand crease of the shoe as the shoe is moved in the U-shaped path.

When the trimming cut has progressed to a point located adjacent to the opposite end of 40 the heel-breast line 106 the operator by tilting the treadle 154 moves the beam 68 in a clockwise direction to cause the trimming portion 38 of the knife to face upwardly and lowers the shoe by stepping on the treadle 114 thereby to form the 45 heel-breast receiving shoulder 31.

When the beam 68 is in neutral position a spring-pressed plunger 162 (Fig. 5) carried by the same engages within a notch 164 formed in the bearing pin 70 under which circumstances the 50 cutting section 38 of the knife 32 is in position for making the beveling cut. When the knife is in position to cut the heel-breast receiving shoulders 30 and 31 the plunger 162 engages within notches 166 and 168, respectively, of the bearing sleeve 55 70. By providing the above detent means the operator may quickly swing the cutting section 38 of the knife from one of the three positions to another.

The trimming portion 38 of the knife may be 60 initially adjusted relatively to the support 40 in directions indicated by arrows 170 (Figs. 2 and 3) by sliding the table 46 along a guideway of the standard 44. Such adjustment may be readily effected by first releasing a set screw 172 which is 65 in threaded relation with the standard and passes through an elongated slot 174 in the table 46 and then turning a hand screw 176 (Fig. 1) which is rotatably mounted in a lug 178 of the standard and is in threaded relation with the table. After 70 the proper adjustment has been made the set screw 172 forces the table 46 into binding relation with the standard 44.

The trimming portion 38 of the knife may be 75 swung into proper adjusted position relatively to the support 40 by turning an adjusting rod 180

having right and left threaded portions which are screwed into swivels 182 and 184, respectively. The swivels 182 and 184 are pivotally connected to a rearwardly extending arm of the housing 52 and to a bracket 186 secured to the table 40, respectively. 5

In order rigidly to secure the shoe 20 upon the support 40 during the sole-trimming operation the machine is provided with the clamp 42 comprising clamping arms 102 (Fig. 7) which are 10 pivotally connected to opposite ends of a bar 186, respectively. The bar 186 is pivotally secured to the upper end of a plunger 188 one side of which is provided with a rack 190 constructed and arranged to mesh with a segmental gear 192 operated by a removable lever 194. A Horton clutch prevents the plunger 188 from being urged upwardly under operating pressure of the arm 189 until a ball 196 which engages the plunger is forced downwardly 20 against the pressure of a spring 198 by a release lever 200. When the plunger 188 is in raised position the arms 102 may be swung laterally to permit the shoe to be placed upon the support 40. A pair of spring-pressed plungers 202 engage notches 204 of the respective arms 102 to retain the same in vertical position. Since the bar 186 is pivotally secured to the plunger 188 the arms 102 may swing to equalize their pressure against the shoe. The 25 bar 186 is normally held in horizontal position by a spring-pressed slide 206 which is constantly urged upwardly by a spring against the under surface of the bar 186. It will thus be clear that as the operating arm 194 is rotated in a counterclockwise direction the arms 102 clamp the sole against the support 40, the ball 196 operating to prevent the arm 194 from releasing the shoe until the ball is forced downwardly by the release lever 200. 40

In order to perform the heel-seat fitting operation the operator, after making the proper adjustments and after marking the heel-breast line 106 on the sole, lowers the support 40 and positions the shoe bottom-side up upon the same. 45 The sole is then clamped to the support by the arms 102 as the operator moves the lever 194 in a counterclockwise direction. The cutter is then tilted to the position illustrated in Fig. 4 and the shoe upon the support 40 is swung around to 50 the starting position. As the shoe upon the support 40 is raised under pressure of the spring 112 the cutting edge of the trimming portion 38 of the knife enters the sole along one end of the heel-breast line to form the heel-breast receiving shoulder 30, the upward movement of the support 40 being limited by contact of the overlasted counter portion 145 (Fig. 8) of the shoe with the portion 150 (Fig. 5) of the guide member 55 60 34. The beam 68 is then turned to its neutral position, illustrated in Fig. 5, and the heel portion of the shoe is moved in a U-shaped path past the cutting portion 38 to reduce the heel-seat portion of the sole by the beveling cut 26 (Fig. 8). When the beveling cut has progressed forwardly 65 of the sole to a point just rearwardly of the opposite end of the heel-breast line 106 the operator tilts the beam 68 until the plunger 164 engages within notch 166 thus causing the cutting edge of the trimming portion 38 of the knife to face upwardly. The treadle 14 is then depressed to cause the trimming portion 38 to form the heel-breast receiving shoulder 31 at the opposite end of the breast line 106. 70

Having described my invention, what I claim 75

as new and desire to secure by Letters Patent of the United States is:

5. 1. In a heel-seat fitting machine, a support for a shoe, a flexible cutter, mechanism for operating the cutter, guides constructed and arranged to constrain an operating portion of the cutter for movement in a path of predetermined curvature, and means for guiding the support past the operating portion of the cutter to reduce the heel-seat portion of the sole of a shoe on the support.
10. 2. In a heel-seat fitting machine, a support for a shoe, a flexible cutter, means for flexing the cutter to curve the trimming portion thereof, means for moving the cutter relatively to said support, means for clamping a shoe to the support, and means for guiding the support in a U-shaped path past the trimming portion of the cutter to reduce the heel-seat portion of the sole of the shoe clamped on the support.
15. 3. In a heel-seat fitting machine, a cutter provided with an elongated cutting edge, means for moving the cutter lengthwise of its cutting edge, and means constructed and arranged to guide the heel end of a sole attached to a shoe upper past the cutter thereby to reduce the heel-seat portion of the sole and to form heel-breast receiving shoulders upon the same, said cutter being mounted for transverse tilting movement to facilitate the formation of the heel-breast receiving shoulders.
20. 4. A heel-seat fitting machine having, in combination, a flexible knife having an elongated cutting edge, guides constructed and arranged to constrain an operating portion of the knife for movement in a path of predetermined curvature, means for moving the knife lengthwise of its cutting edge, and means for guiding a shoe having an attached sole in a U-shaped path past said cutting edge to reduce the heel-seat portion of the sole for the reception of a heel.
25. 5. A heel-seat fitting machine having, in combination, a flexible cutting blade provided with an elongated cutting edge, mechanism for moving the blade lengthwise of its cutting edge, and means for guiding a shoe in a predetermined path past the blade, said blade being mounted for transverse tilting movement.
30. 6. A heel-seat fitting machine having, in combination a flexible strip knife mounted for transverse tilting movement, means for flexing the knife to curve the cutting portion thereof, means for oscillating the cutting portion of the knife lengthwise of its cutting edge, and means for guiding the sole of a shoe in a predetermined path past the cutting portion.
35. 7. A heel-seat fitting machine having, in combination, a flexible strip knife, means for flexing a portion of the knife, means for oscillating the knife lengthwise of its cutting edge, mechanism for tilting the knife transversely, and means for guiding a shoe past the flexed portion of the knife to reduce the heel-seat portion of the sole of the shoe for the reception of a heel.
40. 8. A heel-seat fitting machine having, in combination, a cutter provided with a curved cutting edge, means for moving the cutter lengthwise of said edge, a support for a shoe, and mechanism for guiding the support relatively to the cutter to reduce the heel-seat portion of a shoe on the support, said cutter being mounted for transverse tilting movement to form heel-breast receiving shoulders upon the sole as the shoe is moved relatively to the cutter.
45. 9. A heel-seat fitting machine having, in combination, a flexible cutting blade, spaced mem-
- bers for flexing the blade to curve the trimming portion of the blade, means to move the blade lengthwise of its cutting edge in a path determined by said members, and means for guiding a shoe past the trimming portion to reduce the heel-seat portion of a sole attached to the shoe, said members being mounted for pivotal movement about an axis extending generally along the cutting edge of said trimming portion.
50. 10. A heel-seat fitting machine having, in combination, a cutter, guide members, means for moving the cutter lengthwise of its cutting edge in a path determined by said members, a support for a shoe movable toward and away from the cutter, mechanism for normally urging the support toward the cutter, one of said guide members being constructed and arranged to limit movement toward the cutter of the shoe mounted upon the support, and means for guiding the support in a U-shaped path past the cutter as the shoe engages said one guide member thereby reducing the heel-seat portion of the sole of the shoe.
55. 11. A heel-seat fitting machine having, in combination, a knife provided with an elongated cutting edge and mounted for lateral tilting movement, guide members, means for moving the knife lengthwise of its cutting edge in a path determined by said guide members, a support for a shoe mounted for movement toward and away from the knife, a clamp for securing the shoe to the support, resilient means for normally urging the support toward the knife, one of said guide members being constructed and arranged to limit movement of the shoe mounted upon the support toward the knife, and means to guide the support in a U-shaped path past the knife as the shoe engages said one guide member for reducing the heel-seat portion of the sole.
60. 12. A heel-seat fitting machine having, in combination, a strip knife provided with a cutting edge, members for flexing the knife to curve the cutting portion thereof, means for moving the knife lengthwise of its cutting edge, a support for a shoe, means for moving the support toward and away from the knife, and means for moving the support in a U-shaped path past the knife to reduce the heel-seat portion of the sole of the shoe, said knife being constructed and arranged to be tilted transversely to vary the angle between the knife and the general plane of the sole thereby to cause the knife to form heel-breast receiving shoulders upon the sole as the shoe is moved relatively to the knife.
65. 13. A heel-seat fitting machine having, in combination, a flexible cutting blade, members for flexing the blade to curve the cutting portion thereof, means for moving the blade lengthwise of its cutting edge, a support for a shoe, means for moving the support in a rectilinear path toward and away from the knife, and means for guiding the support in a U-shaped path past the blade to reduce the heel-seat portion of the sole, said blade being mounted for transverse angular movement to cause the blade to be disposed at varying angles of the general plane of the sole thereby to cause the blade to form heel-breast receiving shoulders upon the sole as the shoe is moved in said rectilinear path.
70. 14. A heel-seat fitting machine having, in combination, a flexible cutting blade, a support for a shoe, spaced members for flexing the blade to curve the cutting portion thereof to which work may be presented, and a blade-engaging brace positioned between said members to insure that the cutting section is not distorted by pressure of
75. 75

work presented thereto, said member and said brace being mounted for transverse tilting movement with respect to the support.

15. A heel-seat fitting machine having, in combination, a flexible cutting blade, means comprising a member for flexing the blade, shoe supporting means movable toward and away from said blade, and means for normally urging the shoe-supporting means toward the blade, said member having a surface which substantially merges with a side of the cutting blade and is constructed and arranged to engage the overlasted counter portion of a shoe mounted upon said supporting means thereby to limit the movement of the shoe toward the blade.

16. A heel-seat fitting machine having, in combination, a flexible cutting blade movable lengthwise of its cutting edge, a member for flexing the blade, a shoe support movable toward and away from the blade, and means for urging the shoe support toward the blade, said blade-flexing member being provided with a surface which substantially merges with a side of the cutting blade and is constructed and arranged to engage a shoe mounted upon the support thereby to limit movement of the shoe toward the blade, said blade and said blade-flexing means being mounted for angular movement to vary the angle of the blade relatively to the shoe-supporting means.

30 17. A heel-seat fitting machine having, in combination, a flexible strip knife, spaced members for flexing the knife to curve the cutting portion thereof, means for moving the cutting portion of the knife lengthwise of its cutting edge, said knife-flexing members being mounted for relative adjustment to vary the curvature of the cutting portion of the knife, a shoe support movable toward and away from the knife, and means for urging the shoe support toward the cutting portion of the knife, one of said members having a surface constructed and arranged substantially to merge with the knife and to engage a shoe mounted upon the shoe support thereby to limit movement of the shoe toward the knife.

45 18. A heel-seat fitting machine having, in combination, a flexible cutting blade movable lengthwise of its cutting edge, spaced members constructed and arranged to flex the blade and to guide the same thereby to curve the cutting section of the blade, said members being mounted for relative adjustment thereby to vary the curvature of said cutting section, a shoe support movable toward and away from said cutting section, and means for urging the support with yielding pressure toward the blade, one of said blade-flexing members having a surface constructed and arranged to merge with a side of the cutting blade and to engage the overlasted counter portion of a shoe mounted upon the support thereby to limit movement of the shoe toward the blade, said blade and said members being mounted for angular adjustment to vary the angle at which the blade is disposed relatively to the shoe support.

60 19. A heel-seat fitting machine having, in combination, a blade having an elongated cutting edge, a member provided with a slot for receiving the blade and having a pair of converging faces which merge substantially with opposite sides of the blade respectively, means for guiding a shoe past the blade, and means for oscillating the blade to reduce the heel-seat portion of the

sole of the shoe as it is guided past the blade for the reception of a heel.

20. A heel-seat fitting machine having, in combination, a strip knife, a member provided with a slot constructed and arranged to guide the knife, said member being provided with a pair of converging faces which merge substantially with opposite sides of the knife respectively, means for tilting said member and said knife transversely, means for guiding a shoe past the knife, and means for oscillating the knife to reduce the heel-seat portion of the sole of the shoe guided past the knife.

5 21. A heel-seat fitting machine having, in combination an elongated knife, a member provided with a slot through which the knife passes, said member having a pair of converging faces which merge substantially with opposite sides of the knife respectively, means for guiding a shoe past the knife, and means for oscillating the knife 10 to reduce the heel-seat portion of the sole of the shoe guided past the knife for the reception of a heel, said member being mounted for pivotal movement about an axis disposed substantially in alinement with the portion of the cutting edge of 15 the knife positioned within said slot.

22. In a heel-seat fitting machine, a blade having an elongated cutting edge, blade guiding members, one of said members being provided with a pair of converging surfaces which merge 20 with opposite sides of the blade respectively, and means for oscillating the blade lengthwise of its cutting edge, said one member being pivotally movable about an axis extending substantially lengthwise of said cutting edge.

30 23. In a heel-seat fitting machine, a knife provided with an elongated cutting edge, means for moving the knife lengthwise of said edge, and means for guiding the heel end of a sole attached to a shoe upper past the knife to reduce the 35 heel-seat portion of the sole and to form heel-breast receiving shoulders upon the same, said knife being mounted for tilting movement about an axis which is substantially coincident with said cutting edge to facilitate the formation of 40 heel-breast receiving shoulders.

45 24. In a heel-seat fitting machine, a cutter provided with an elongated cutting edge, means for moving the cutter lengthwise of its cutting edge, means for guiding the heel end of a sole 50 attached to a shoe upper past the cutter to reduce the heel-seat portion of the sole and to form heel-breast receiving shoulders upon the same, means for tilting the cutter transversely, and a detent for determining the degree of tilting 55 movement of said cutter to facilitate the formation of heel-breast receiving shoulders.

60 25. A heel-seat fitting machine having, in combination an elongated knife, a member provided with a slot through which the knife passes, said member having a pair of converging faces which merge substantially with opposite sides of the knife respectively, means for guiding a shoe past the knife, means for reciprocating the knife to reduce the heel-seat portion of the sole of the 65 shoe guided past the knife for the reception of a heel, said member being mounted for pivotal movement about an axis disposed substantially in alinement with the portion of the cutting edge of the knife positioned within said slot, and a 70 detent for locating the knife in different angular positions about said axis.

CHARLES G. BROSTROM.
